UNITED STATES PATENT OFFICE.

GREEN FREEZE, OF CLIFFORD, ILLINOIS, ASSIGNOR OF ONE-HALF TO JOHN DRAPER,
OF CLIFFORD, ILLINOIS.

DOOR-OPERATING DEVICE.

1,361,707.

Specification of Letters Patent.

Patented Dec. 7, 1920.

Application filed August 6, 1920. Serial No. 401,809.

To all whom it may concern:

Be it known that I, GREEN FREEZE, a citizen of the United States, residing at Clifford, in the county of Williamson and State 5 of Illinois, have invented certain new and useful Improvements in Door-Operating Devices, of which the following is a specification.

This invention relates to improvements in 10 an apparatus for opening and closing doors, more particularly to the doors in the galleries and passageways of mines and similar localities, and has for one of its objects to provide an apparatus of this character operative by an approaching vehicle or draft animal, which will be automatically closed when the opening mechanism is released by the departure of the vehicle or animal.

With these and other objects in view, the 20 invention consists in certain novel features of construction as hereinafter shown and described and then specifically pointed out in the claims, and in the drawings illustrative of the preferred embodiment of the invention.

Figure 1 is a plan view of the improved apparatus installed in a conventional mine gallery or passage and partly in section.

Fig. 2 is a longitudinal sectional elevation 30 on the line 2-2 of Fig. 1.

Fig. 3 is a transverse section on the line 3-3 of Fig. 1.

The improved apparatus may be installed 35 in connection with many kinds of passageways in which doors are employed but is designed more particularly for use in connection with the doors in mine galleries and passageways, and for the purpose of illustration is shown thus applied, the floor of 40 the gallery being represented at 10, the side walls at 11 and the roof or ceiling at 12. The usual mine car track 13 is located upon the floor 10.

The doors are represented at 14, and are 45 movable when open into pockets 15 in the side walls 11.

A transverse track 16 is supported from the ceiling 12, and hanger devices 17 are connected to the adjacent upper corner of each 50 door and travel upon the track. If required short tracks 18 will be located in the bottoms of the pockets 15 upon which supporting wheels 19, carried by the doors, travel, to support the outer portions of the doors and

coöperate with the hangers 17 to support the 55 door and reduce the friction.

Attached to the adjacent edges of the doors 14 are supporting rods 20, and attached to each rod is a link device 21.

Attached to the side walls 11 in any suitable manner are guide rods 22 spaced a considerable distance from the doors and each provided with a spring 23.

Pivoted at 24 to each end of each of the links 21 is a bar or rod 25, each rod being 65 directed reversely oblique from its pivoted end toward the rods 22, and at their outer ends the bars are curved laterally and terminate in eyes 27 engaging respectively around the rods, and against the springs as shown. 70

The springs thus exert a constant force against the rods and maintain the doors yieldably closed or with their confronting edges in close proximity.

By arranging the bars reversely oblique, 75 they present elongated V-shaped sockets above the tracks 13, so that a vehicle, such as a mine car approaching from either direction will engage the bars and move their contiguous ends toward the walls 11 and 80 carry the doors into open position. This action of the bars compresses the springs 23.

The car or other vehicle while passing through the doorway retains its pressure 85 against the bars 25 and links 21, and when the vehicle passes beyond the doors the pressure against the bars at the departing side is removed so that the reaction of the springs 23 will close the doors.

The doors are thus operative by a vehicle 90 approaching from either side.

The bars 25 are also operative by a draft animal approaching from either direction, the collar of the horses acting on the bars.

The apparatus is simple in construction, 95 positive and sure in its action, and requires no attention from the occupant of the vehicle or the driver of the animals.

The preferred embodiment of the invention is disclosed in the drawings and set 100 forth in the specification, but it will be understood that any modifications within the scope of the claims may be made in the construction without departing from the principle of the invention or sacrificing any of its 105 advantages.

Additional springs 28 may be employed to coact with the springs 22, to render the

return of the doors to closed position more certain.

What is claimed is:

1. In an apparatus of the class described, a closure movable transversely of a passageway, a bar directed obliquely to the pathway of the closure and movably connected to the same, and a spring exerting its force constantly longitudinally of the bar.
- 10 2. In an apparatus of the class described, coacting closures movable away from and toward each other transversely of a passageway, bars movably connected to the closures and directed reversely oblique to the pathways of the same, and a spring exerting its force constantly longitudinally of each bar.
- 15 3. The combination with a passageway having laterally directed pockets communicating therewith, a track transversely of the passageway, closures having hangers engaging said track and movable into said pockets, a bar movably engaging said closure and directed obliquely to the path of the same, and a spring exerting its force constantly longitudinally of the bar.

4. In an apparatus of the class described, a closure movable transversely of a passageway, a bearing rod attached to the outer edge of the closure, a link attached to said rod, a bar pivoted at one end to said link and directed obliquely to the path of the closure, and a spring exerting its force constantly longitudinally of the bar.

5. In an apparatus of the class described, a closure movable transversely of a passageway, a guide rod, a spring upon the rod, a bar directed obliquely to the pathway of the closure and movably connected at one end to the same and slidale at the other end upon the rod and against the spring, the spring exerting its force constantly longitudinally of the bar.

In testimony whereof I affix my signature hereto.
